CULTURE FLASK OR SIMILAR ARTICLE

Paul A. Rohde, Baltimore, Md., assignor to Baltimore Biological Laboratory, Baltimore, Md., a corporation of Maryland

Filed Aug. 22, 1967, Ser. No. 8,344

Term of patent 14 years

(Cl. D16—1)

FIG. 1

FIG. 2

FIG. 3

FIG. 4

FIG. 5

FIG. 1 is a side elevational view, the opposite side being substantially a mirror image thereof, of a culture flask or similar article showing my new design;

FIG. 2 is a top plan view thereof;

FIG. 3 is a bottom plan view thereof;

FIG. 4 is a front elevational view thereof; and

FIG. 5 is a rear elevational view thereof.

The dominant features of my design reside in the portions shown in full lines.

I claim:

The ornamental design of a culture flask or similar article, substantially as shown and described.
